UNITED STATES PATENT OFFICE.

LUTHER A. POWELL, OF WARRIOR, ALABAMA.

SAD-IRON.

1,146,650.

Specification of Letters Patent. Patented July 13, 1915.

Application filed April 21, 1914. Serial No. 833,553.

To all whom it may concern:

Be it known that I, LUTHER A. POWELL, a citizen of the United States, residing at Warrior, in the county of Jefferson and 5 State of Alabama, have invented certain new and useful Improvements in Sad-Irons; and I do hereby declare the following to be a full, clear, and exact description of the invention, such as will enable others skilled in 10 the art to which it appertains to make and use the same.

This invention relates to improvements in sad irons, and the primary object of the invention is the provision of a sad iron 15 having the ironing body thereof hollow for the insertion thereinto of heated liquid, for the purpose of heating the iron to the desired temperature for ironing or smoothing the clothes.

20 With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters of reference designate like or corresponding parts 30 throughout the several views, and in which:—

Figure 1 is a side elevation of the improved sad iron showing a portion of the cover broken away. Fig. 2 is a top plan 35 view of the improved sad iron showing the handle removed therefrom and a portion of the cover of the iron broken away to expose the manner of attaching the cover to the body portion of the iron. Fig. 3 is a cross sectional view on the line 3—3 of Fig.

40 Fig. 4 is a detail plan view of the cover for the upper open end of the sad iron. Fig. 5 is a detail perspective view of the means for attaching the cover to the body of the 45 iron.

Referring more particularly to the drawings, 1 designates the ironing face of the sad iron, which is formed upon the bottom plate 2. The bottom plate 2 of the sad 50 iron has an upstanding shell 3 formed upon its upper surface, which shell extends completely around the base 2 and is mounted inwardly a short distance from the edge of the upper face of the base plate 2 and tapers 55 inwardly so as to provide an artistic appearance for the iron, as is clearly shown in Fig.

3 of the drawings. The shell 3 being formed upon the base plate 2 forms a cavity in the body portion of the iron, which cavity is provided for the reception of a heated liquid, such as boiling water or the like.

A sheet of asbestos or other similar material is mounted about the outer surface of the shell 3 and entirely encompasses the same, providing means for retaining the heat 65 within the interior of the shell and causing the heat to radiate out through the base plate 2 of the iron, instead of through the sides or the shell 3. The sheet 4 of asbestos or similar packing material is held in place 70 by a sheet 5 of any suitable type of sheet metal which is positioned about the outer surface of the sheet 4 of packing and entirely encompasses the same. If it is so desired the sheet 5 may be plated with any 75 suitable type of metal such as nickel plating, gold plating, this feature being left to the discretion of the person manufacturing or using the device.

The upper end of the body of the sad iron 80 is open, and the lid 6 is mounted thereupon, for forming a closure for the cavity formed within the body of the iron. The cover 6 is constructed of any suitable type of sheet metal and it has its marginal edges overlapping the upper marginal edges of the plate 5, as is clearly shown at 7 in Fig. 3 of the drawings. A washer 8 of flexible material, such as soft leather or the like is positioned interiorly of the cover 6 and engages the upper end of the shell 3, the plate 5 and the plate 4 of packing material, for forming a fluid tight connection between the cover 6 and the body of the iron, which body is composed of the various plates and the shell heretofore described.

The shell 3 has securely riveted thereto and adjacent its upper marginal edge a plurality of brackets 10, which brackets have laterally projecting lugs 11, which lugs are 100 provided with transverse screw threaded openings 12. The openings 12 receive the ends of thumb screws 14, which thumb screws are carried by the lid or cover 6 and the thumb screws coacting with the screw 105 threaded openings in the lugs securely hold the cover 6 upon the upper open end of the sad iron.

An opening extends through the cover 6 substantially equidistant of its ends, which 110 opening has communication with the interior of the iron body and forms an egressing

opening for air from the interior of the iron. A cap or closure 15 is mounted upon the upper protruding end of the pipe 16, which pipe is mounted in the egressing opening 5 which is formed in the lid 6.

A length of pipe 17 is securely attached in any suitable manner to the cover 6 of the iron and it has communication with the cavity or interior hollow portion of the iron 10 body. The pipe 17 has its outer end flared and is provided for the purpose of permitting the entrance of a heated liquid into the interior of the iron. A stopper 18 is attached to the pipe 17 by any suitable type 15 of flexible member such as a chain or cord 19.

A handle 20 is attached to the iron by supporting braces 21, which braces are attached to the cover in any suitable manner, 20 and the handle 20 has a collar or flange 22 formed thereupon and extending entirely about the circumference of the same substantially equidistant of its ends so as to prevent the slipping of the hand when gripping the iron handle in ironing or smoothing 25 various articles of apparel.

In using the improved iron as has been heretofore described, the plug or stopper 18 is removed from the open flared mouth of 30 the pipe 17 and heated liquid poured into the cavity formed within the iron body, which heats the iron to the desired temperature for ironing or smoothing clothes. When the heated liquid is being poured 35 within the interior of the iron body, the cap 15 is removed from the short length of pipe 16 so as to permit the egress of the air from the interior of the iron. By filling the interior of the iron with a heated liquid, the 40 iron is heated to the proper temperature

for efficiently ironing or smoothing clothes, and owing to the heat retaining qualities of the liquid, the iron will remain heated much longer than is ordinary in the case of irons which are constructed solidly of metal. If 45 it is desired the iron may be filled with a warm or cool liquid and placed upon a stove or other suitable heating means and heated until the water reaches the desired temperature. 50

In reducing the invention to practice certain minor features of construction, combination and arrangement of parts may necessitate alterations to which the patentee is entitled provided such alterations are comprehended within the scope of what is claimed. 55

What is claimed is:—

In a sad iron structure, a base plate having an ironing face formed thereupon, a 60 hollow upstanding shell formed on said base a short distance from its edges and extending completely around said base, an outer covering of non-heat conducting material secured to and completely encompassing the outer surface of said shell, a metallic plate encompassing and securing said covering to the shell, brackets secured to the inner upper marginal edge of said shell, a removable cover provided with downwardly 65 extending ends overlapping the edges of the plate, means for securing said cover to the brackets and a handle secured to the cover. 70

In testimony whereof I affix my signature in presence of two witnesses.

LUTHER A. POWELL.
